UNITED STATES PATENT OFFICE.

EDWIN R. STORM, OF NEW YORK, N. Y.

PERFORATOR.

SPECIFICATION forming part of Letters Patent No. 622,088, dated March 28, 1899.

Application filed January 9, 1897. Serial No. 618,579. (No model.)

To all whom it may concern:

Be it known that I, EDWIN R. STORM, a citizen of the United States, and a resident of New York, county and State of New York, 5 have invented certain new and useful Improvements in Perforators, of which the following is a specification.

This invention relates to perforating-machines.

10 The main object of the invention is to provide an improved machine for punching holes in ribbons of paper or other suitable material, such as are used for making and breaking a telegraph-circuit in certain forms of automatic telegraphs, the holes being suitably arranged relatively to each other in the ribbon, so that when it is drawn through a suitable telegraph transmitting apparatus in circuit with a distant receiver the desired message 15 will be sent. Each message will be composed of letters, characters, syllables, or words, each of which is represented on the ribbon by a distinguishable combination of holes.

In this machine the punches are not moved 20 directly by the operator, but by mechanism operated by a motor and brought into co-operation with the punches when the operator moves a finger-key. There are as many keys as distinct characters—that is, one key for 25 each distinct combination of perforations representing a letter, syllable, or word to be made. Each key controls the number and arrangement of punches which will be moved forward at a time, and consequently the number and 30 arrangement of holes punched in the ribbon. Each character—that is, the holes representing it—is completely punched automatically on the operation of the corresponding key, and after the holes are punched the ribbon is 35 automatically moved forward a distance equal to the space occupied on the ribbon by that character plus the space between two consecutive characters.

By means of the spacing device employed 40 in my improved machine it becomes possible to save the time required to strike a key for the spaces between words, since the mechanism controlling the spacing is so arranged that by depressing the space-key coincident with 45 any character-key the space is prolonged to the proper distance between words.

In this machine there are preferably three

rows of punches, the central row being designed to form a central row of holes at regular distances apart in the ribbon being perforated and with which pins in the periphery of a feed-wheel in the telegraph-transmitter with which the ribbon is to be used engage to draw the ribbon along. The two outer rows of punches are designed to form character-holes—that is, holes in different combinations to represent and to transmit different characters. The number and relative positions of the two rows of punches can be varied, and many features of the machine would be useful if the feed-hole punches were omitted and the feed-holes were separately punched or omitted.

The machine shown and described herein is the same in character as that set forth in 70 my Patent No. 575,497, dated January 19, 1897, but includes several improvements hereinafter described and particularly pointed out in the claims.

In the drawings, Figure 1 is a view showing the general arrangement of parts of the apparatus, the inclosing case being broken away. Fig. 2 is a section on line 2^a 2^a. Fig. 3 is a plan view of the top of the machine, the keyboard not being shown. Fig. 3^a is a 80 plan of a modification. Fig. 4 is a sectional view of the punch-head on a larger scale. Fig. 4^a is a perspective of a part of the punch-head. Fig. 5 is a perspective view of the sliding head. Fig. 6 is a partial perspective 85 view showing a sliding head with a different form of block. Figs. 6^a and 6^b are side views, at right angles to each other, of a detached block. Figs. 7 and 7^a show, respectively, side and sectional views of the joint between bars 90 48 and 54. Fig. 7^b is an enlarged section of part 54. Fig. 8 is a detail view of the tension device. Fig. 8^a is a view, partly in section, of portions of the tension device detached. Fig. 8^b is a like view of a modification. Fig. 95 9 is a sectional view showing a joint. Figs. 9^a and 9^b are side views, on a smaller scale than Fig. 9, of two detached parts of said joint. Fig. 10 is a perspective view of a socket-block. Fig. 11 is a plan view of the 100 spacing device. Fig. 12 is a sectional view of the spacing device. Fig. 13 is a perspective view of the spacing device. Fig. 14 is a view of the clutch. Fig. 15 is a sectional

view of clutch, showing the bifurcated trip. Fig. 16 shows the stop and returning-spring. Fig. 17 is a side view of a part of the machine-frame with a modified tension device thereon. Fig. 18 is a detail of the paper-moving device. Figs. 19 and 19^a are respectively bottom, plan, and side views of a modified paper-feeding device. Fig. 20 is a detail of arm to keep paper in alinement, and Fig. 21 is a detail of punch-head. Fig. 22 is a similar view of a punch-head without a row of holes for a central row of punches. Fig. 23 shows a cushioned arm attached to the lifting-bar detached from the machine. Fig. 24 is an enlarged side view of a pawl. Fig. 25 is a perspective view, on a larger scale, of one end of the space-bars, looking from below. Fig. 26 is a plan view of the trip-pieces; and Fig. 27 is a partial plan view of the spacing-blocks, operating-rods, and intermediate blocks.

A represents a base, to which are secured frame-pieces A' A², parallel-bar frame A³, cushion-pieces A⁴ A⁴, socket-bars A⁵ A⁶, and cushion-piece A⁷, Figs. 1 and 2. To uprights A' A² is secured a top plate or frame B, Figs. 1, 2, and 3, provided with boxes 11, fitted with segments 2, Fig. 16, wear being taken up by screws 2' 2". The boxes form bearings for shaft 3, having a clutch 4 with a bifurcated trip, hereinafter described, wheels 5 6, and cams 7 8 9. Screw 2" is placed back of the bearing, Figs. 15 and 16, to prevent loss of motion due to wear of the bearing.

35 5 is a fly-wheel, and 6 a pulley or gear-wheel secured thereto, to which power is applied from any suitable motor. Wheel 5 is loose on shaft 3, but held in position between clutch 4 and nut 5', which is locked by set-screw 5",

40 Fig. 14.

Cam 7, formed with a projection 7' on one side, Fig. 4, operating on wheel 10, loosely revolving on shaft 11, fixed in the sliding head 12, moves the head forward. The two cams 45 8 act upon straps 13, formed on the links 14, which are connected by the joint 15 to lifting-bar 16, which slides vertically in ways 17, and raise and lower said lifting-bar and with it the cushioned arm 16', attached thereto, 50 16" being the cushion, which is on the side of arm 16' toward the parallel bars. In Patent No. 575,497 I have shown cams 8 of such irregular shape that they operate to first raise, second, hold stationary, third, lower, 55 and, fourth, hold stationary the lifting-bar, each movement occupying practically one-quarter of a revolution, but have found in practice that this construction does not operate perfectly when the machine is run at a

60 very high speed. I have in the improved machine herein shown employed eccentrics or cams 8 having regular curved peripheries, preferably true circles. While these theoretically are always moving the lifting-bar up or down, there will be a time between the main up-and-down movements when the lifting-bar will be practically at rest, and this

time is sufficient to allow the punch-operating device 12 to operate the selected punches before the blocks are withdrawn from behind them. Owing to the improved construction the machine can be run more rapidly and runs more smoothly than the machine of said patent. Rapid and smooth operation is further increased by use of the spring 19 and a cam 7, that only positively operates the device 12 in one direction. Cam 9 operates the paper or ribbon moving device.

Sliding head 12, working on ways 18, fixed to plate B, is provided with retractile spring 80 19, a drawback-plate 20, socket 21, and grooves 22. The retractile spring, fastened at one end by screw 23 to sliding head 12 and at the other end by post 24 to top plate B, tends to draw head 12 back, holding wheel 10 against cam 7. The drawback plate or fork 20 has projections 25, adapted to work against collars 26 on punches 27 28 in such manner as to draw the punches backward with head 12. Both outer punches 27 and middle punches 28 90 work in holes 29 in punch-head 30. Holes 29 are enlarged at their outer ends 31, so that punchings will readily escape. The punch-head 30 is secured to top plate B, provided with rabbet 32, Fig. 4, to insure the proper 95 placing of the punch-head and to resist the shock or thrust of the punches. Punch-head 30 is provided with a ribbon-receiving slot or way 30'.

100 Socket 21, Figs. 2, 3, 4, and 5, receives and guides block 33, adapted to slide through the socket and along rabbet 34, which is in a plane between the planes occupied by the upper ends of blocks 35. Block 33 serves to fill the space between head 12 and the inner ends of 105 the central row of punches. Punches 28 in my improved machine are provided with a spring 28', Figs. 4 and 4^a, to move the punches forward with the drawback-plate 20, that block 33 may be free to enter behind punches. 110 The spirals 28" of the springs occupy notches 28^x in the punch-supporting block and the ends of the spring rest in grooves 28^z, being held in place by a top plate. Grooves 22, 115 formed in the sliding head to receive blocks 35, are spaced to bring blocks in line with the punches, one block back of each punch, and to permit blocks 35 to rise and fall freely in a vertical line.

120 Blocks 35, operated by rods 36, links 37, and parallel bars 38, are adapted to slide in grooves 22 and have a longitudinal channel 39, connecting with a transverse hole 40 to receive the formed end of rods 36, Fig. 4. These blocks are shown in two parallel series on different levels, one series being in position to coöperate with the lower row of punches and the other series in position to coöperate with the upper row, and when raised serve to fill the space between head 12 and the ends of punches 27. These blocks may be circular in section instead of rectangular, (see 35', Fig. 6,) in which case instead of grooves 22 there would be circular holes 35^a.

Rods 36, provided with eyes 41, fitted to channels 42, formed in links 37, are held to place by screws 43. (See Fig. 9.) Links 37 are attached by rods 44 to frame-piece A' and are jointed to parallel bars 38, which are jointed at the other end to links 45, which are provided with channels 42, in which are fitted the eyes 41 of rods 46, secured to place by screws 43. Links 45 are fastened by rods 47 to frame-piece A³, Fig. 1. This construction causes bars 38 when moved to continue parallel to their original positions, so that rods 36 46 will be moved the same distance which ever assembling-bar 48, placed underneath 15 and working against bars 38, is operated. Parallel bars 38, links 37 45, rods 36 46, and blocks 35 are in this machine nearly balanced by springs 49, having one end fixed to link 37 and the other end to adjusting-screws 50 in 20 top plate B, Figs. 1 and 2. The parallel bars 38 rest on cushions A⁴ A⁴.

The assembling-bars 48, pivoted by pins 51 to blocks 52, resting on cushions A⁷, furnished with the projections 53, are operated by the 25 lifting-bar 16 through catch-bars 54. The blocks 52, bored for pins 51, have an edge channeled to receive the ends of the assembling-bars 48 and are halved on and fastened to the recessed bar A⁵, which is secured to 30 base A, Fig. 2. Cushion 55 is formed of felt, rubber, or other material let in channeled bar A⁷, secured to frame A. Projections 53 on assembling-bars 48 are so arranged on each bar as to come in contact with the particular bars 38, controlling punches 27, required to form 35 the character desired. There are as many bars 48 as characters for which the machine is arranged. The catch-bars 54 terminate in handles 56, have projections 57 58, holes 59 40 60, and are jointed to the assembling-bars in such manner as to allow them to move on center 61, Figs. 2 and 7. Preferably each catch-bar 54, of which there is one for each assembling-bar, is formed with a circular depression 45 62, into which the rounded end of its assembling-bar 48 fits and in which it is held by screw 63, Figs. 7^a and 7^b. The projections 57 are made to fit over and engage lifting-bar 16 when catch-bars 54 are moved forward in 50 position. (Shown in dotted lines in Fig. 2.) Projections 58 come in contact with the oscillating frame 64 on a rock-shaft and oscillate it when the catch-bars are moved forward to engage bar 16. Holes 59 are furnished with 55 swivels 59', to which are fastened retractile springs 65, one for each catch-bar 54. The other ends of springs 65 are held by screws 66, with set-screws 67, to tension-bar 68, which works in ways 69 and has regulating-screws 70, Fig. 2. Holes 60, which receive rods 71, communicate with semicircular recesses or channels 60 on the rear sides of catch-bars 54 to receive the eyes on the ends of rods 71, as shown by dotted lines in Fig. 2. The rods are threaded 65 at one end and screwed into pieces 72. Pieces 72 are jointed at 73 with finger-keys 74, having tips 79, and move on fulerums 75 in block 76,

channeled to receive the keys. Block 76 is fastened by V projection 77, fitting into a corresponding groove in bar A⁶, fastened to base 70 A, and by screws 78. The several banks of keys are so pivoted on fulerums 75 as to equalize the leverage as nearly as possible and consequently the force or touch required on each key to draw its catch-bar 54 forward and overcome the resistance of spring 65.

Rock-shaft frame 64, working on pivot-points 80, normally held against projections 58 by spring 81, is provided with an arm 82, attached to rod 83, jointed at 84 to stem 85 of trip-piece 86, Figs. 1, 2, 14, and 15, forming one member of the bifurcated trip of clutch 4. In this machine the stem works loosely in fixed block 87 to allow the trip-piece to have a backward-and-forward as well as an upward-and-downward motion. Trip-piece 86 being normally held backward against wedge-shaped end 88 of fixed block 87 by spring 89, Fig. 15, is made to engage bolt 90, which is adapted to slide in clutch 4, and is provided with a transverse 90 groove 91, into which fits trip-piece 86 to draw the sliding bolt backward or release it, as required. Spring 92 tends to press the bolt forward into holes 93, sunk in balance-wheel 5, locking wheel 5 by clutch 4 to shaft 3. The 95 other member of the bifurcated trip, which is extension 88 of fixed body 87, is wedge-shaped and fits against enlarged end 4' of clutch 4 in such manner that as the clutch revolves, carrying with it bolt 90, it enters groove 91 in 100 the bolt and partially withdraws it, compressing spring 92, the wedge-shaped extension being purposely formed a little too narrow to completely withdraw the bolt from holes 93. Completion of the withdrawal of said bolt 105 is effected by part 86 entering groove 91 as piece 88 leaves it, (see Fig. 15,) which has one face beveled to match and complete the wedge shape of 88 and is made a little thicker than necessary to engage the bolt from the balance-wheel. A shoulder 4² on the enlarged end 4' limits the upward movement of trip-piece 86 and prevents said trip-piece from striking or catching on the bottom of groove 91. By 110 making this extension a fixed member of the bifurcated trip the thrust of the shaft, acting through the bolt, is taken by said extension and the frame supporting it until the thrust is no longer in the direction of movement of the movable part of the bifurcated trip, but 115 is across such direction, acting against the frame, but not against the spring 81, which holds the movable member of the trip against the bolt. Hence a light spring will serve to 120 hold said movable part in place and a light 125 touch on the keys will withdraw it. Spring 89 is compressed by the resistance which spring 92 offers to the withdrawal of the bolt from hole 93, which is effected near the close of each revolution of shaft 3. Bolt 90 is 130 formed longer than clutch 4 that end 94 may engage with spring 95 when the bolt is withdrawn from holes 93. Spring 95, held at one end by post 96 and regulated by screws 97

and 98, acts against end 94 of bolt 90 after it has been withdrawn from the drive-wheel and overcomes the inertia of shaft 3 and tends to return it to proper position should inertia 5 have carried it too far, while spring 89, compressed by the resistance to a complete withdrawal of bolt 90, moves trip-piece 86 with the shaft when returned by spring 95. Were piece 86 movable only vertically, the bolt 10 sliding along its inclined surface and disengaged thereby from the wheel would, upon the return of shaft 3, by spring 95 slide back against the wheel and partially engage with holes 93, producing a clicking noise as the 15 wheel continues to rotate, and would soon wear the holes and the end of the bolt, making engagement uncertain. Giving piece 86 the backward-and-forward motion and using spring 89 overcomes said evils and makes the 20 piece 86 automatically adjust itself to any change in the bolt or in its position. Screw 97 increases the tension of spring 95. Screw 98 regulates the position to which the shaft is returned.

25 Rods 46, Figs. 1 and 12, attached to links 45, are formed so their upper ends work freely in holes 99 in block 100, secured to top plate B. Block 100 is formed with bearings 101 102, Figs. 11 and 13, which receive sliding rod 30 103, formed with a head 104, fitted to work in slot 105, moved forward by lever 106, fulcrumed at 107, and actuated by one of the two space-key levers 74, Figs. 1, 11, and 13, jointed by the single finger-tip 108. Rod 103 and lever 106 are returned to position by spring 109. On sliding rod 103 are blocks 110, freely moving in planes perpendicular to the rod and held in position by pins 111 112, so as to move forward and then backward in a body. 40 Ends 113 of blocks 110 rest in rabbet 114 in block 100, resting over or upon the ends of rods 46 and actuated by them, but when resting on rabbet 114 are free to move under ends 115 of blocks 116, fulcrumed on rod 117 45 and provided with retractile springs 118, attached to rod 119. Rods 117 and 119 are fixed to top plate B. Blocks 116 are provided with pins 120, which are staggered and set to work against the adjoining left-hand block in such 50 manner that all the blocks to the left are raised with the last block, as in Fig. 13. Each block has one pin 120, which projects on the left side only to a distance nearly equal to the thickness of the adjoining block. The 55 blocks are of uniform length; but the reduced ends 115 are made alternately long and short, as shown at 115^a and 115^b, and the short ends have notches 115^c. From each bar with a long end a pin 120 extends into the notch of 60 the next bar and from each bar with a short end a pin extends under the long end of the next bar, as clearly shown in Fig. 25, which is an inverted view of several ends 115 with their pins. Ends 121 of blocks 116 are cut 65 to form shown, forming in series a sectional ratchet or rack, into which works pawl 122 in arm 123, jointed by pin 124 to lever 125.

Pawl 122 is held to place by spring 126 and arm 123 works over ends 121, being held to place by top guide 127 and side guides 128 70 129. (See Figs. 3 and 12.) Lever 125, fulcrumed at 130, is moved toward head 30 by spring 131 and is returned to position by cam 9, working against the end 125'. One end of spring 131 is secured to top plate B by screw 75 132 and the other end to lever 125 through hole 133. Lever 125 is provided with and reciprocates rods 134 135, rod 134 being a connecting-rod between lever 125 and block 33. Rod 135, jointed to lever 125 by pin 136, has one end furnished with a rack or series of teeth 80 137, working in pinion 138, fixed to feed-wheel 139, preferably provided with pins 140, adapted to fit in the feed-holes punched in the paper strip, feed-wheel 139, working on shaft 85 141, fixed in top plate B. Rack 137 is held against pinion 138 to mesh with it by the arm 142, Figs. 3 and 18, during movement in one direction of each reciprocation, arm 142, having the indent 143, fulcrumed by screw 144 to top 90 plate B. The indent 143 is formed to receive end 145 of lever 146, fulcrumed at 147 to top plate B. Lever 146, bent to pass underneath rack 137, is provided with teeth 148, spring 149, and end 150, formed to work on cam 151 95 150 on one end of cam 8. Teeth 148 engage pinion 138 and lock it. Spring 149 tends to disengage teeth 148 and pinion 138 to move end 145 out of indent 143, (see Fig. 3,) forcing arm 142 toward pinion 138, compelling rack 100 137 to mesh with and operate it. End 150 works against cam 151, shaped to force teeth 148 in engagement with pinion 138 and formed end 145 in indent, freeing rack 137 from pinion 138 during part of the revolution of shaft 3 105 and allowing the retractile spring 149 to act during remainder of the revolution. Piece 152, fastened to top plate B, is formed to hold the paper strip on feed-wheel 139. Where a center line of feed-holes is not used, the lever 110 153, fulcrumed at 155 to top plate B, with roller 154, Figs. 19 and 19^a, pressing against feed-wheel 139, may be used. Lever 153 is provided with retractile spring 156. Piece 157, fastened to top plate B, is formed to lift 115 the strip from feed-wheel 139 and direct it out from the machine.

The working parts described, except keys 79, drive-wheels 5 6, slot 30', feed-wheel 139, and pieces 152 157, are protected by a cover C, 120 formed so that a portion C' will guard the finger-keys and a portion C² will serve to hold copy.

The strip or ribbon moved forward by feed-wheel 139 from a suitable reel 158 passes over 125 arm 159, through tension device 160, under arm 161, in slot 30', and over feed-wheel 139, under the piece 152 and in front of the piece 157 and out from the machine. Reel 158, fastened to top plate B by arm 162, has a loose 130 spool 163 freely working on fixed shaft 164, Figs. 1 and 3. Spool 163 has two spurs 165 to engage with the wooden core of a paper-roll and a ratchet-wheel 166 on its lower edge,

operated by pawl 167, jointed to arm 168, fulcrumed at 169 to top plate B and operated by retractile spring 170 and link 171. The pawl 167 is controlled by arm 159, fulcrumed at 173 to arm 162. Arm 159 and pawl 167 are connected by spiral spring 174. Retractile spring 170 is jointed to arm 168 at 175 at one end, the other being secured by a screw 176 to top plate B. Link 171, jointed to arm 168 by screw 177, rests against head 12 and is moved forward by it, retractile spring 170 returning it to position. When manifolding of the strip is required, additional reels may be used, operated through the arm 168 by 15 additional pawls 167 or by rolls superimposed on the loose piece 163 and fixed shaft 164.

Tension device 160 is composed of a fixed plate 178, Fig. 8, movable plate 179, adjusting-screw 180, compression-spring 181, spur 182, guide-pin 183, and cover-plate 184. The fixed plate contains a hole for reception of the guide-pin and is rabbeted on top to form a check or stop for cover 184. The bottom of the rabbet is bored and tapped to receive a screw 185 to adjust the cover 184 to the width of the paper strip. The movable plate 179 is fitted to work on bottom piece 186, is bored to receive the end of guide-pin 183 and point of spur 182, which holds the movable plate 20 against the fixed plate through the action of compression-spring 181, which may be made to fit inside, as in Fig. 8^a, or over the spur, as in Fig. 8^b. The force of compression-spring 181 is regulated by screw 180 working in arm 25 187. Arm 187 supports the pivot of top piece 184. The fixed plate 178 is attached to arm 188, fulcrumed at 189 and regulated by spring 190 and tension-screw 191, or is attached to body 192, Figs. 17 and 3^a, sliding in groove 30 in top plate B, made parallel with slot 30'. Body 192 is held in groove 193 by screw 194 in slot 194', Fig. 3^a, and washer 195 and is acted upon by retractile spring 196, having one end attached to washer 195 and the other 35 end attached to arm 197. Arm 161, fulcrumed on pin 198, controlled by screw 199 and compression-spring 200, Fig. 20, prevents the paper strip from jumping up in slot 30' and losing its alinement.

Fig. 3^a is a plan view showing a tension device, such as shown in Fig. 17, suitably mounted on plate B, the pawl-lever 168 being so shaped and arranged as not to interfere with the necessary movement of the tension device.

Figs. 21 and 22 show, respectively, groupings of punch-holes in head 12 and of punches for preparing perforated strips with and without a central row of feed-holes.

The operation of the described mechanism is as follows: An operator desiring to produce in a ribbon or in ribbons perforations corresponding to any particular character or combination of characters presses down the key 65 on which it appears, turning it on its fulcrum 75, which causes rod 71 and the corresponding catch-bar 54 to move, carrying projection 57

over lifting-bar 16 to the dotted position in Fig. 2. The same movement carries projection 58 on the same bar against the rock-shaft 70 arm or frame 64, turning it on its axis and carrying with it arm 82, pulling down rod 83 and trip-piece 86, which permits bolt 90, pressed out by spring 92, to move into engagement with the drive-wheel 5, locking it by means 75 of clutch 4 to shaft 3. This is all that the touch of the operator on the key has to do—namely, to move one bar 54 to engage bar 16 and to pull down the movable member of the trip to release bolt 90, connecting the drive-wheel to the shaft. All other movements are produced automatically by the mechanism and driving-motor. Shaft 3, being thus put in motion, turns cams 7 8 9. The two cams 8, acting through straps 13 and links 14, cause the 85 lifting or moving bar 16 to rise, cams 8 being set to effect this in a little less than half a revolution. The lifting-bar, being under projection 57 of the catch-bar moved forward by a key, raises it, lifting the corresponding assembling-bar 48. Projections 53 on the assembling-bar being so disposed as to engage with the particular parallel bars 38 necessary for the formation of the desired character press up and move those bars directly over 90 the projections, leaving all others at rest. This moves the corresponding links 37 45, which raise rods 36 46. Rods 36 move blocks 35 upward in the sliding head 12 behind punches 27. Rods 46 work through the block 100 against ends 113 of blocks 110, causing the blocks 110 to turn on rod 103. These blocks, having ends 113 under ends 115 of blocks 116, cause blocks 116 to move on rod 117, raising end 115 and depressing end 121. The blocks 105 116, having pins 120, lift as one block all the blocks from the first block (at the left in Fig. 13) to the last block moved, so that any block lying between blocks moved and not moved directly by rods 46 will have its end 121 depressed. The arm 123, with pawl 122 attached to lever 125, acting under the retractile force of the spring 131, moves over the depressed ends 121 until pawl 122 engages with the first end 121 not depressed. Movement of arm 123 115 is retarded by the shape of cam 9, acting on end 125' of lever 125, and carries rod 135 with rack 137, which, being now unlocked, frees itself from pinion 138 and the rod 134 toward the punch-head. Rod 134 is connected with 120 block 33, sliding in the socket 21, and pushes the block behind feed-hole punches 28. Shaft 3, which has been continuously rotated by wheel 5, since the clutch was engaged by movement of a key, causes cam 7, by its projection 125 7' acting on roller 10 on shaft 11, to move head 12 and the punches 27 28, behind which blocks 35 33 have been placed, as above described, to perforate the ribbon previously placed in the slot 30'. Continued revolution 130 of cam 7 permits spring 19 to pull back head 12 with drawback-plate 20, which withdraws the operated punches. Cam 151, releasing end 150 of lever 146, permits spring 149 to

draw back end 145, which, acting on the arm 142, forces the rack 137 into mesh with pinion 138, locking the rack thereto. Cam 9 in the second half of its revolution engages 5 with lever 125, moving it, with arm 123, rods 134 135, and block 33, to their original positions. Rod 135, moving rack 137, locked to pinion 138, moves the pinion, feed-wheel, and ribbon thereon forward a distance corresponding to the length of the character being punched plus the space between the characters. Piece 152 holds the ribbon against the feed-wheel. Pins 140 draw the strip forward into position to have another character 10 punched therein by the next operation of either character-key. Shaft 3, having nearly completed one revolution, brings clutch-bolt 90 into engagement with the wedge-shaped projection 88 of the bifurcated trip and as 15 20 25 30 35 40 45 50 55 60 65 70 75 80 85 90 then used, no space-blocks will be moved and but a single feed-hole punch will be operated.

Rod 134 may be omitted, if desired, and block 33 left permanently behind feed-hole punches. The effect would be that all the feed-hole punches would move forward with each forward movement of head 12. In forming characters requiring the whole number of feed-holes all the feed-hole punches would 5 punch holes; but in forming characters requiring a less number of feed-holes as many of the forward punches in the series as necessary would punch the paper, but the following punches would simply pass through 10 holes punched at the preceding operation 15 without resistance.

Having described my invention, I claim—

1. In a perforator, the combination of punches, a shaft normally at rest, cams 20 thereon for operating the perforator, a driven wheel normally loose on said shaft, a clutch on the shaft, and a retarding-spring adjacent to the clutch, said clutch having a bolt adapted to be engaged with and disengaged 25 from the wheel, and when engaged being incapable of reaching the retarding-spring, and when disengaged extending so as to strike said retarding-spring.

2. In a perforator, the combination of 30 punches, a shaft normally at rest, cams thereon for operating the perforator, a driven wheel normally loose on said shaft, a clutch on the shaft, and a retarding-spring adjacent to the clutch, said clutch having a bolt adapted to be engaged with and disengaged from 35 the wheel, and when engaged being incapable of reaching the retarding-spring, and when disengaged extending so as to strike said spring, a trip for the clutch, and finger-keys connected with the trip to operate it.

3. The combination of punches and means 40 for rendering them operative in different combinations, including blocks, assembling-bars, parallel bars operated thereby, links operated by the parallel bars, rods movable with the parallel bars and links for actuating the blocks, and springs, attached to the links to diminish the weight and shock of the moving parts.

4. The combination of punches normally 45 inoperative, keys, a shaft, cams thereon having regular curved peripheries adapted to raise and lower the parts moved thereby with a regular and continuous movement, a lifting-bar operated by said cams, and intermediate parts moved by the lifting-bar to render some of the punches operative, a punch-moving device, and means for moving it.

5. The combination of punches normally 50 inoperative, keys, a shaft, cams thereon having regular curved peripheries adapted to raise and lower the parts moved thereby with a regular and continuous movement, a lifting-bar operated by said cams, and intermediate parts moved by the lifting-bar to render some of the punches operative, a punch-moving device, a cam on the shaft arranged

to positively move said device in one direction only, and a spring 19 for returning said device.

70

6. The combination, in a perforator having punches, a power-actuated head for operating them, blocks movable behind the punches in different combinations, means for moving said blocks consisting of a lifting-bar, catch-bars, keys connected to the catch-bars so as to operate them, assembling-bars and parallel bars moved by the catch and lifting bars, parts between the parallel bars and said blocks to transfer movement to them, and an arm movable with the lifting-bar and in such relation to the parallel bars as to insure their return to original position on the return of said lifting-bar.

75

7. The combination, in a perforator having 80 punches, a power-actuated head for operating them, blocks movable behind the punches in different combinations, means for moving said blocks consisting of a lifting-bar, catch-bars, keys connected to the catch-bars so as to operate them, assembling-bars and parallel bars moved by the catch and lifting bars, parts between the parallel bars and said blocks to transfer movement to them, and an arm extending from the lifting-bar over the parallel 85 bars and cushioned on its side toward said parallel bars.

90

8. The combination, in a perforator, of punches movable in different combinations, blocks movable behind the punches, said 95 blocks having longitudinal grooves 39 and communicating transverse holes 40, rods 36 with formed ends occupying said grooves and holes, keys, and means brought into operation thereby for moving said rods and blocks. 105

100

9. The combination, in a machine having a ribbon to be advanced by steps of varying lengths, of a feed-wheel, a propelling-rack, a lever connected with the rack, an arm jointed to the lever, a series of space-bars for determining the length of movement of the lever, a series of rods operating the space-bars, a series of finger-keys, and means brought into use thereby to operate said rods and bars. 110

110

10. The combination, in a machine having 115 a ribbon to be advanced by steps of varying lengths, of a feed-wheel, a propelling-rack, a lever attached thereto, a series of pivoted space-bars, a series of rods operating the space-bars for increasing the number of 120 spaces the feed-wheel is advanced, a series of finger-keys, means brought into use thereby to operate said rods and bars and means, as a pawl, moving with the rack and lever and co-operating with the space-bars to limit movement of the feed-wheel.

125

11. The combination, in a machine having a ribbon to be advanced by steps of varying lengths, of a feed-wheel, a propelling-rack, a lever attached thereto, an arm pivoted to the 130 lever and engaging with a series of pivoted space-bars, a series of rods operating the space-bars, a series of bars between the rods and space-bars, a series of finger-keys, a series

of parallel bars and links to which the rods are connected, and intermediate devices between the keys and bars.

12. The combination, in a machine having a ribbon to be advanced by steps of varying lengths, and having a ribbon-feed wheel and means for operating it, of space-bars, a series of rods, a series of bars between the rods and space-bars for operating the space-bars, adapted to be moved between the rods and space-bars so that the rods will operate a greater number of space-bars and increase the length of step by which the ribbon is advanced, a pawl coöperating with the space-bars for limiting movement of the feed-wheel, and means, as a spring, for returning the intermediate bars to their original position.

13. The combination of several punches, means for operating them in different combinations, keys for selecting the combinations, a lever with arm and rod with rack thereon, a ribbon-feed wheel with a pinion engaging with said rack, pivoted spacing-bars, engaging with the arms, and means connecting the keys and spacing-bars, whereby the spacing-bars moved and the movement of the lever with its rack depends upon the key operated.

14. The combination in a machine having a ribbon to be advanced by steps, keys for operating the machine, a feed-wheel, a propelling-rack with means for operating it, controlling space-bars, operating-rods therefor, means for connecting the keys and rods, bars between the rods and space-bars, adapted to move between the rods and space-bars so that the rods will operate a greater number of space-bars, and means for connecting said bars movable between the rods and space-bars to a separate spacing-key, whereby upon the simultaneous depression of this separate key and either character-key, the number of steps the ribbon is advanced is increased.

15. The combination of lever 125, arm 123, rod 135 with rack 137, a ribbon-feeding wheel with pinion, space-bars to engage with the arm and limit movement of the lever, means as a spring for advancing the arm, keys and intermediate connections controlling the movement of the space-bars and hence length of movement of the lever, and means for returning the lever to its original position, the rack engaging with the pinion and advancing the feeding-wheel a distance corresponding to the movement of the lever.

16. The combination of lever 125, a rod, with rack thereon, a ribbon-feeding wheel, means for moving the lever, a cam adapted to return the lever and turn the feed-wheel, a block 33 connected to and also moved with said lever, and punches rendered operative by said block.

17. The combination of bars 38, pivoted links 45, rods 46, space-bars 116, and a ribbon-feed controlled thereby.

18. The combination of bars 38, links 45, rods 46, bars 116, punches, block 33, and

means controlled by bars 116, for moving block 33 behind the punches.

19. The combination of bars 38, links 45, rods 46, space-bars 116, a ribbon-feed wheel, block 33, an intermediate device between bars 116 and block 33 and feed-wheel, keys, and means operated thereby moving bars 38 in desired combinations.

20. The combination of lever 125, a feed-wheel, means carried by the lever for moving the feed-wheel, keys, and means including space-bars brought into use by the keys and a coöperating pawl for controlling movement of the lever, and cam 9 for returning the lever to its original position, thereby moving the feed-wheel the desired distance.

21. The combination of feed-wheel 139, having a pinion 138, rack 137 adapted to engage therewith, arm 142, adapted to hold the rack 85 against and in mesh with the pinion or release it from the pinion, and means for moving the rack.

22. The combination in a machine having a strip to be advanced by steps, of a feed-wheel 90 having a pinion, means as a rack for advancing it in one direction, a lever separate from the rack and having teeth or projections adapted to mesh with the pinion and move the feed-wheel backward and forward to exact 95 position and hold it while the rack is out of gear therewith.

23. The combination in a machine having a strip to be advanced by steps, of a feed-wheel, having a pinion thereon, means for advancing it in one direction, a lever having teeth thereon, adapted to mesh with the pinion, a cam, adapted to work against the lever and move it against and into mesh with the pinion, and hold it.

24. The combination of a feed-wheel, having a ratchet-wheel thereon, a rack adapted to engage therewith, an arm adapted to hold the rack against and in mesh with the ratchet-wheel or to release it, a toothed lever, with means for engaging the arm and operating it, and adapted to engage its toothed portion with the ratchet and a cam working against the lever and operating it.

25. The combination of a feed-wheel having pinion thereon, a rack, an arm, a toothed lever, with a spring, a cam and means for operating it, whereby on the movement of the cam against the toothed lever the toothed portion is forced in mesh with the pinion adjusting and holding the feed-wheel to exact position, and the arm is liberated allowing the rack to free itself from the pinion, and upon the further movement of the cam the spring is allowed to act on the toothed lever, so as to cause it through the arm to hold the rack in mesh with the pinion and liberating the toothed lever from the pinion, and means for moving the rack and the feed-wheel.

26. The combination with a feed-wheel, of an operating-rack, a reciprocating body carrying the same, keys, means operated by

- power independent of the keys but brought into operation by the keys, for moving the rack and body forward a greater or less distance according to the amount of feed required, space-bars and a pawl to determine the distance the rack can move and means as cam 9, and parts moved thereby for returning the rack and body to their original positions.
27. The combination with a ribbon-feeding device of a ribbon-tension device consisting of a head, with adjustable means for holding and restraining the movement of a strip or ribbon, mounted on a movable part having a tension-spring.
28. The combination with a ribbon-feeding device, of a ribbon-tension device, consisting of a head, having a fixed and movable part between which the strip or ribbon is passed, a tension-screw with spring and pin working therein and holding the movable part against the ribbon, a movable arm or body to which the head is fastened and a tension-spring.
29. The combination with a ribbon-feeding device, of a ribbon-tension device, consisting of a head having a fixed and movable part between which the strip or ribbon is passed, a tension-screw with spring and pin working therein, means for guiding the bottom edge of the strip or ribbon and an adjustable cover 184, for guiding the top edge of the strip a movable arm or body to which the head is fastened, and a tension-spring attached to the movable arm or body.
30. The combination with the punch-head of a ribbon-feeding device a reel, having a member working loosely on a spindle, a lever 168, with a pawl adapted to move said member, and link 171 between the lever and the punch-head for moving the lever.
31. The combination with a ribbon-feed device of a reel having a member with a ratchet-wheel attached, working loosely on a spindle, a lever with pawl adapted to engage with said ratchet-wheel, an arm 159, with spring 174, adapted to engage and disengage the pawl and ratchet wheel, a spring 170, for moving lever 168 in one direction and means as link 171 for connecting lever 168 with power-driven devices for operating said lever.
32. The combination, in a tension device for paper strips, of a fixed plate, a spring-pressed movable plate facing the fixed plate and a cover-plate extending over the space between said fixed and movable plates to prevent sidewise movement of the paper strips.
33. The combination, in a tension device for paper strips of a fixed plate, a spring-pressed movable plate facing the fixed plate and a pivoted and adjustable cover-plate extending over the space between said fixed and movable plates to prevent sidewise movement of the paper strips.

Signed this 7th day of January, 1897.
EDWIN R. STORM.
